Primary Examiner — Jack Reickel*Assistant Examiner* — Bobby W Jones II(74) *Attorney, Agent, or Firm* — Alan G. Towner; Leech Tishman Fuscaldo & Lampl(57) **CLAIM**

The ornamental design for an oil absorbent skimmer, as shown and described.

DESCRIPTION

FIG. 1 is a top isometric view of an oil-absorbent skimmer showing our new design;

FIG. 2 is a bottom isometric view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines are for environmental purposes only and form no part of the claimed design.

1 Claim, 8 Drawing Sheets(56)
